UNITED STATES PATENT OFFICE.

WILLIAM A. KING, OF MEMPHIS, TENNESSEE.

DESIGN FOR AN AUTOMOBILE-RADIATOR.

55,473.

Specification for Design.

Patented June 15, 1920.

Application filed April 12, 1920. Serial No. 373,402. Term of patent 14 years.

To all whom it may concern:

Be it known that I, WILLIAM A. KING, a citizen of the United States, residing at Memphis, in the county of Shelby and State of Tennessee, have invented a certain new, original, and ornamental Design for an Automobile-Radiator, of which the following is a specification.

The design is illustrated in the accompanying drawing, which is made a part hereof, wherein—

Figure 1 is a view of the ornamental radiator frame in front elevation,

Fig. 2 is a view of the radiator frame in side elevation, and

Fig. 3 is a view of the radiator frame in top plan.

The radiator frame has its lateral and top edges beveled as indicated at 10, it being the intent that the frame shall be combined with a hood being also similarly tapered, chamfered corners 11 are also provided which co-act with continuous ribs extending along the hood and body of the car

to which it is applied but which of course form no part of the present invention. The entire structure is tapered, being wider at the bottom or base than at the top, so that the side walls are tapered not only relative to a vertical line but are also tapered relative to a plane coinciding with the major axis and perpendicular to the plane of the front. In other words all of the edges of the radiator except the bottom or base are tapered in two directions, both to the vertical line and to the plane as above noted.

I claim,

The ornamental design for an automobile radiator herein shown and described.

In witness whereof I have hereunto set my hand and seal at Memphis, Tennessee, this 9th day of April, A. D., nineteen hundred and twenty.

WILLIAM A. KING. [L. s.]
